US00D866891S

(12) **United States Design Patent** (10) **Patent No.:** **US D866,891 S**
(45) **Date of Patent:** ** *Nov. 12, 2019

(54) **SCOURING ARTICLE**

(71) Applicant: **3M INNOVATIVE PROPERTIES COMPANY**, St. Paul, MN (US)

(72) Inventors: **Lauren K. Carlson**, St. Paul, MN (US); **Robert J. Maki**, Hudson, WI (US); **James P. Endle**, New Richmond, WI (US); **David C. Raithel**, Hudson, WI (US)

(73) Assignee: **3M INNOVATIVE PROPERTIES COMPANY**, Saint Paul, MN (US)

(*) Notice: This patent is subject to a terminal disclaimer.

(**) Term: **15 Years**

(21) Appl. No.: **29/552,554**

(22) Filed: **Jan. 22, 2016**

(51) LOC (12) Cl. **07-05**

(52) U.S. Cl. **D32/40**
USPC .....

(57) **CLAIM**

The ornamental design for a scouring article, as shown and described.

DESCRIPTION

FIG. 1 is a perspective view of a scouring article showing the new design;

FIG. 2 is a top view thereof;

FIG. 3 is a bottom view thereof;

FIG. 4 is a front view thereof, the rear view being a mirror image of the front view shown; and,

FIG. 5 is a left side view thereof, the right side view being a mirror image of the left side view shown.

The broken lines define boundaries of the claim and form no part thereof.
